UNITED STATES PATENT OFFICE.

PAUL J. McCARROLL, OF BOSTON, MASSACHUSETTS, ASSIGNOR TO UNDERWOOD TYPE-WRITER COMPANY, OF NEW YORK, N. Y., A CORPORATION OF DELAWARE.

TYPE-WRITING MACHINE.

1,319,167.

Specification of Letters Patent.

Patented Oct. 21, 1919.

Application filed January 25, 1918. Serial No. 213,796.

To all whom it may concern:

Be it known that I, PAUL J. McCARROLL, a citizen of the United States, residing in Boston, in the county of Suffolk and Commonwealth of Massachusetts, have invented certain new and useful Improvements in Type-Writing Machines, of which the following is a specification.

This invention relates to typewriting machines of the kind in which superposed plies of web are led into the machine to be written upon, copies being made upon the underlying plies by means of carbon sheets. This invention is an improvement upon the construction of the Wernery & Smith Patent, No. 1,182,055, dated March 16, 1915.

It is sometimes a practice to use the Wernery & Smith machine for separate plies of web loosely superposed, and the principal feature of my invention relates to side-edge guides for the webs. Where the webs are of uniform width and arranged laterally in register with one another, they may be guided by means of suitable side guides, as is the custom; but where some of the webs are narrower than others, a difficulty arises, because the usual side guides do not answer for the narrow webs. This is because said side guides must be separated by a distance equal to the width of the widest web, thus leaving the narrow webs uncontrolled and affording an opportunity for them to shift from side to side. As it is desired that the typed items shall fall in certain columns or allotted spaces upon each web considered widthwise, the main object of my invention is to provide for the lateral guiding of narrow webs under these circumstances.

To accomplish this purpose, I utilize the blades on said Wernery & Smith machine that project between the plies of web and are used as carriers or shifters for carbon sheets. These blades are mounted upon a slide or carrier, which shifts the carbons backwardly to present the carbons to fresh portions of the webs from time to time.

I provide one or more of these carbon-shifting blades with means upon their free ends to serve as side guides for the loose webs. The webs may all be in alinement or register with one another along one side, but out of register along the opposite side; and the guides upon the carbon-shifting blades are utilized for confining as many of the

webs as may be of under-width, so that all of the webs may be sufficiently controlled and guided to the platen of the typewriting machine. These guides shift backwardly with the carbon carriage, and serve to bring the sheets laterally into alinement during such backward shifting of the carriage.

Other objects and advantages will hereinafter appear.

In the accompanying drawings,

Figure 1 is a side sectional elevation of an Underwood typewriting machine provided with the present improvements.

Fig. 2 is a detail view, illustrating one method of holding a carbon sheet to a shifting blade in operative position under a web or work-sheet.

Fig. 3 is a view similar to the preceding, but shows a different means of attachment for securing the carbon around the blade.

Fig. 4 is a perspective view of the carbon carrier, with a plurality of carbon-shifting blades of different lengths, respectively, adapted to guide webs of correspondingly varying widths.

Fig. 5 is a transverse section of the said carrier, with the blades thereon, looking rearward.

Fig. 6 is a detached view, in perspective, of one of the shifting blades.

Fig. 7 is a cross-section, similar to Fig. 5, but showing a different arrangement of the said shifting blades.

Fig. 8 is a sectional view, illustrating one of the carbon-carrying blades having a clip; the blade in this view being reversed, whereby the clip is seen upon the opposite edge of the blade from the position occupied at Fig. 2; and the carbon sheet accordingly is folded back over the clip, so that the carbon may extend from the blade in the same general direction as at Fig. 2.

The loosely superposed webs or plies 10, 11, 12 and 13, of various widths, are led from any suitable source of supply up to a guide 14, at the rear of the typewriting machine, and pass forwardly to the revoluble platen 15, feeding around the underside and up in front thereof. The carbon sheets 16, interposed between the plies, are attached to blades or carriers 17, which extend inwardly from the sides of a carriage or slide 18, which is arranged in rear of the typewriter platen, and has a handle whereby it

may be shifted back to carry the carbon to fresh portions of the webs. As set forth in said patent, the platen is shifted bodily to enable the webs to be straightened out to 5 permit this backward shifting of the carbons.

All of the webs may be guided along one set of their side edges by suitable guides, as 19, and corresponding guides 20 may be 10 placed at the opposite edge of the widest web. To guide any narrow web against a sidewise displacement, one end of the carbon-carrying blade, which underlies said narrow sheet, may be turned up to form a 15 side guide 21. If said blade is to underlie a broader sheet, the end of the blade is bent reflexly, as at 22, to overlie a portion of the margin of the narrow sheet, so as not to stand up under the overlying wide sheet; 20 the reflex or bent end occupying so little room vertically as to be negligible. Thus, the narrow sheet is guided along one edge by the guide at the projecting end of the carbon-carrying blade, and at the other edge 25 it is controlled by the guides which are common to all of the webs. Hence, lateral displacement of any web is prevented.

These special guides 21 and 22 for the narrow sheets are mounted only upon the 30 carbon-carriage 18, but have sufficient control over the narrow sheets to keep them substantially in their true paths, so that when they feed around the platen they are in proper lateral register with the wide 35 sheets and with one another. The backward thrust of the carriage or slide 18, upon which these blades are mounted, operates to adjust or true up along the edges such of the webs as may have become laterally displaced 40 in the rear of the carbon-carriage; and their registration is thus obtained with sufficient accuracy to serve for the usual purposes, so that the typing falls at the desired widthwise portions of all the sheets.

45 The end of the carbon sheet 16 may be wrapped around its blade 17 and pasted back upon the body of the sheet, as suggested in Fig. 3; the web which is guided by the side guide 21 or 22, provided on said 50 blade, lying upon the carbon. There is also illustrated at Figs. 2 and 6 the usual clip 23 for clipping the carbon sheet to the blade, and it will be understood that this clip is sufficiently short to clear the reflex bend 55 22 of the blade which serves as a side guide and retainer for the narrow sheet. In this case, the said narrow sheet rests upon the surface of the clip.

It will also be understood that any narrow 60 sheet may be guided on one edge by either one of the opposite main or general side guides 19 or 20, and controlled at the other edge by the guide at the end of the underlying carbon-carrying blade 17, as at 65 Fig. 4, in which it is seen that the narrow

sheets are not all in register at either side. At Fig. 7 is illustrated an arrangement whereby the wide and narrow sheets are all in register along one side edge, but out of register and controlled by separate gages or 70 guides along the opposite side edge.

It will thus be seen that the carbon-carrying blade may successfully perform a double duty, retaining control of the carbon, as in said Wernery & Smith patent, and also 75 preventing displacement of narrow webs, thus substantially increasing the range of usefulness of the machine. The device is simple, inexpensive and compact, and not troublesome to use. Any blade may be detached from its seat 24 and replaced by another blade of greater or less length, having a side guide for the sheet at its free end, so that an assortment of blades of varying lengths may render the machine adaptable for a large variety of uses. The reflex or bent-back portion of the blade may serve to keep the carbon sheet from rising, especially during the backward thrust of the carbon-carriage, which straightens out the 80 webs, so that the webs cannot escape over the tops of the guides during the straightening-out operation.

Any of the carbon-carrying blades for the narrow sheets may be arranged upon either 95 of the stepped supports seen at Fig. 4. If the blades have clips 23 thereon, as at Figs. 2 and 6, some of these clips will be in normal positions, forking over the rear edges of the blades, as at Fig. 2, while others will 100 be in reversed positions, forking over the front edges of the blades, as at Fig. 8; and in the latter case, the carbon is placed wrong side out upon the blade, and is finally folded back over the clip, as seen at Fig. 8, so that 105 the carbon extends from the blade 17 in the same direction as at Fig. 2. Thus, only one style of clip 23 needs to be employed for all of the blades. Where the blades are mounted upon the left-hand supports, the clips 23 110 will appear as at Figs. 2 and 6; but if any blade is turned end for end and mounted upon the right-hand support, the carbon is to be held thereon in the manner seen at Fig. 8.

115 Variations may be resorted to within the scope of the invention, and portions of the improvements may be used without others.

Having thus described my invention, I claim:

120 1. In a typewriting machine, the combination with means for leading loosely superposed webs of various widths interleaved with manifolding material to the printing point, and a platen releasably engaging the same at one part, of means for shifting said manifold material relatively to the webs, said means being provided with a guide for each edge of each web.

125 2. In a typewriting machine, the combi-

- 5 nation with means for leading a web and a carbon sheet releasably held together around a revoluble platen, of a shifter transversely attached to the carbon and having a turn-up portion serving as a side guide for the web along one edge.
- 10 3. In a typewriting machine, the combination with a platen releasably engaging a web superimposed upon a carbon sheet, of a shifter extending transversely of the latter and having a reflex bend slidable along one edge of the overlying web in engagement therewith.
- 15 4. In a typewriting machine, the combination with a platen releasably engaging superposed webs of various widths and carbons inserted therebetween, of shifters for the carbons individually controlling the overlying webs, the uppermost shifter having an upturned portion adapted to slide along the top web at one side thereof, and the other shifters being reflexly bent each over the superlying edge of its respective web.
- 20 5. In a typewriting machine, the combination with a releasable platen and means for guiding thereto loosely superposed webs interleaved with manifolding material, of a reciprocable carrier for said material following said webs as they advance toward said platen and thereafter receding from the platen while the manifolding material is being shifted to fresh portions of the webs, and means on said carrier for individually guiding the loose webs, so as to maintain their true positions relatively to the manifolding material during the shifting operation.
- 25 6. In a typewriting machine, the combination with a platen releasably engaging loosely superposed webs interleaved with manifolding material, of a carrier arranged to follow said webs and said material as they advance to the printing line on said platen, and to recede therefrom so as to permit shifting the manifolding material relatively to the webs, and means on said carrier individually guiding the loose webs while the manifolding material is being shifted.
- 30 7. In a typewriting machine, the combination with a carriage supporting a web superimposed upon a carbon sheet, of a carbon shifter attached at one end to said carriage and having means on its free end serving as a side guide for the loose web.
- 35 8. In a typewriting machine, the combination with means for leading a web superimposed upon a carbon sheet, of a carriage for the carbon, a blade projecting from one side of said carriage so as to slide under the web, means on the free end of said blade slidably engaging the edge of the web nearer the opposite side of the carriage, and a clip intermediately securing the carbon to the blade.
9. In a typewriting machine, the combination with means for leading loosely superposed webs and intermediate carbon sheets, of gages arranged to guide both the webs and the carbons at opposite sides thereof, and shifters for the carbons individually adapted for slidable engagement with adjacent webs.
- 10 10. In a typewriting machine, the combination with means for leading loosely superposed webs of various widths and carbons inserted therebetween, of lateral gages for the widest web, shifters for the carbons movable coincidently with said gages, and means on said shifters individually controlling the alinement of the narrow webs along either one of their edges.
- 15 11. In a typewriting machine, the combination with means for leading superposed webs of various widths all alined at one side and carbons interleaved therewith, of gages on both sides of the widest web, shifters for the carbons extending transversely thereof from said alined side of the superposed webs, and retainers on the free ends of said shifters slidably engaging the corresponding edges of the narrow webs.
- 20 12. In a typewriting machine, the combination with a platen releasably engaging loosely superposed webs of various widths and carbons interleaved therewith, of a carriage arranged to travel forwardly with the conjoined webs and carbons, and rearwardly to bring the carbons to fresh portions of the webs, gages on said carriage at both sides of the widest web, and shifters for the carbons coacting with one of said gages in maintaining the narrow webs properly positioned relatively to the carbons.
- 25 13. In a typewriting machine, the combination with means for leading loosely superposed webs and intermediate carbon sheets, of a forwardly located guide, a carriage for the carbons reciprocable rearwardly thereof, gages on said carriage at both sides of the widest web, and carbon shifters secured at one end in proximity to one of said gages and formed with retainers at the other end adapted for slidable engagement with the narrow webs.
- 30 14. The combination with a revoluble platen around which releasable loosely superposed plies of web are fed, of carbon carriers to occupy positions between the plies of web, and a support for said carriers; certain of said carriers having individual gages for the side edges of plies of web.
- 35 15. The combination with a revoluble platen around which releasable loosely superposed plies of web are fed, of carbon carriers to occupy positions between the plies of web, and a support for said carriers; certain of said carriers having individual gages for the side edges of plies of web.

web, said gages being at different points, to enable them to gage superposed plies of different widths.

16. The combination with a revoluble platen around which releasable loosely superposed plies of web are fed, of carbon carriers to occupy positions between the plies of web, and a support for said carriers; certain of said carriers having individual gages for the side edges of plies of web, said carriers being reversible end for end upon said support.

17. The combination with a revoluble platen around which releasable loosely superposed plies of web are fed, of carbon carriers to occupy positions between the plies of web, and a support for said carriers; certain of said carriers having individual gages for the side edges of plies of web, said carriers being reversible end for end upon said support.

vidual gages for the side edges of plies of web, said carriers comprising blades, and said gages being bent up from said blades and being also bent reflexly to overlie the sheets gaged by said gages.

18. The combination with a revoluble platen around which releasable loosely superposed plies of web are fed, of carbon carriers to occupy positions between the plies of web, a support for said carriers; certain of said carriers having individual gages for the side edges of plies of web, and carbon clips between said gages and said support.

PAUL J. McCARROLL.
